[57] ABSTRACT

A numeric readout display utilizing segmented phosphor coated anodes for the presentation of information. The internal mount structure is ruggedized by providing an insulating and lead-spacing glass support therein. Additionally, a novel method of assembly includes making segmented anodes as a one-piece, integral structure, attaching this unit to the leads extending from the lead-spacing glass support and subsequently cutting apart the anode unit to form the segments and applying phosphor thereto.

RUGGEDIZED INTERNAL ELECTRODE
STRUCTURE AND METHOD OF MAKING SAME**

CROSS-REFERENCE TO RELATED APPLICATION

This application is a division of Ser. No. 82,705, filed Oct. 21, 1970, and assigned to the assignee of the present invention.

BACKGROUND OF THE INVENTION

This invention relates to display devices and more particularly to vacuum tube numeric displays utilizing phosphor coated anodes for illumination. Such devices are generally known and are utilized in low voltage operations.

The known devices suffer from a lack of ruggedness and ease of assemblability, particularly in the area of keeping the segmented anodes aligned in the same plane.

OBJECTS AND SUMMARY OF THE INVENTION

It is an object of this invention to obviate the disadvantages of the prior art.

It is another object of this invention to provide a ruggedized display device.

It is another object of this invention to provide a new and novel method of making such devices.

These objects are accomplished in one aspect of the invention by the provision of a lead-spacing, electrically insulating support within a display device envelope. The leads have first and second ends which project in opposite directions from the support. The first ends of the leads are formed to engage the anode segments of the device and the second ends are formed for attachment to conductive pins of the tube base. This structure provides a very rugged mounting for the anode elements.

The novel method of construction comprises first forming the entire anode display as a single integral unit having sections corresponding to the ultimate plural anode configuration. This single unit is mounted upon the leads projecting from the support member and after attachment the separate anodes are formed by cutting out sections of the integral unit. Then all segments are simultaneously phosphor coated. This procedure insures that all anode segments will be in substantially the same plane and greatly reduces the assembly time.

BRIEF DESCRIPTION OF THE DRAWINGS

FIG. 1 is a perspective view of an embodiment of the invention with some parts broken away for clarity;

FIG. 2 is a perspective view of a step in the manufacture;

FIG. 3 is a perspective view of a second step in the manufacturing;

FIG. 4 is a perspective view of a partially completed mount; and

FIG. 5 is an elevational view illustrating one form of phosphor application.

**DESCRIPTION OF THE PREFERRED
EMBODIMENTS**

For a better understanding of the present invention, together with other and further objects, advantages and

capabilities thereof, reference is made to the following disclosure and appended claims in connection with the above-described drawings.

Referring now to the drawings with greater particularity, there is shown in FIG. 1 a vacuum tube numeric readout display device 10 having an evacuated envelope 12. The envelope 12 has at least one transparent viewing area, which in FIG. 1 is shown cut away. Envelope 12 has a substantially tubular body 14 with a sealed-off exhaust tubulation 16 formed at one end thereof and a sealed bottom button 18 closing the opposite end. Button 18 has a plurality of electrically conductive pins, 20a through 20j, extending therethrough.

Mounted within the envelope 12 are a plurality of phosphor coated anode segments 22a through 22g. All of the segments lie in the same plane and each is provided with a rearwardly extending tab, 24a through 24g, respectively, to which an electrical lead is attached. The anode mount comprises an electrically insulating support 26 which can be of glass or ceramic, which holds and spaces apart in a fixed relationship of plurality of leads 28a through 28i. The support 26 is positioned intermediate the ends of the leads 28a through 28i thus leaving a first end of the leads projecting in one direction and a second end of the leads projecting in the opposite direction. The first ends of leads 28a through 28i are connected, as by welding, to the tabs 24a through 24g of anodes 22a through 22g, respectively. The second ends of leads 28a through 28i are connected to conductive pins 20a through 20g.

Lead 28h extends higher than the anode leads and forms part of the top support for the cathodes 30 which are filamentary and positioned in front of, or on the viewing side, of the anode segments. The first end of lead 28h projects into the sealed-off exhaust tubulation 16 and the second end thereof is connected to conductive pin 20h in button 18.

Lead 28i performs only a supporting function as its second end engages substantially the center of conductive pin 20i, which is bent to be substantially parallel to button 18 and which forms the lower support for cathodes 30.

The tenth conductive pin, 20j, extends upwardly from the center of button 18 and is formed to accept a decimal point 32.

The filamentary cathodes 30 are tensioned between conductive pin 20i at the bottom and a pair of spring arms 34 and 36. The arms 34 and 36 extend outwardly from crossbar 38 to which they are connected through the intermediary of springs 40 and 42. The crossbar 38 is fastened to lead 28h.

A getter 44 is positioned in the tube at any suitable location, such as behind the anode array, and can be supported by a rod 45 which is connected to conductive pin 20h at its lower end and to lead 28h at its upper end.

It will be seen that this assembly provides a much more rugged structure than previous devices of this type. The glass support for the leads, in conjunction with the single lead held in the exhaust tubulation, makes this device virtually impervious to shock.

The mount structure itself can be fabricated by the novel method of this invention. Herein, the anodes are first formed as a single integral unit 46, as shown in FIG. 2. The unit 46 has substantially the configuration

of a figure eight with opposed, spaced apart side sections 48 and 50; opposed, spaced apart top and bottom sections 52 and 54 respectively, which are connected to the side sections; and a middle section 56 which is also connected to the side sections. Each of the respective sections is provided with an inwardly extending tab 58, which tabs in the finished device will correspond to tabs 24a through 24g. The unit 46 can be constructed of any suitable anode material such, for example, as nickel or silver plated steel. After unit 46 is formed, the tabs 58 are bent away from the plane of the unit at substantially a right angle as shown in FIG. 3. The first ends of the leads 28a through 28i are now formed to their respective positions and leads 28a through 28g are connected to their respective tabs. After the leads are attached the integral unit is formed into a plurality of anode segments by cutting out the portions thereof where the top, bottom and middle join the sides. The portions are shown in phantom as 60 in FIG. 2. After the cutting operation, which can be performed simultaneously on a jig, the now individual anode segments are coated with phosphor.

An exemplary method of accomplishing the coating is shown in FIG. 5 wherein the anode cluster is dipped onto a suitable surface, such as belt 62 which contains on its surface a layer of phosphor 64 carried in a suitable binder. Subsequent to the phosphor application, the second ends of the leads 28 are formed to contact the conductive pins 20 and connection thereto is consummated. Thereafter, the assembly is completed in normal fashion.

Utilization of this method of assembly greatly enhances the device. All of the anodes lie in the same plane since they were fabricated in this manner instead of being individually attached to the leads. Since the anode segments lie in the same plane, the phosphor ap-

plication by dipping provides a substantially uniform layer on each segment, thus equalizing light output.

While there have been shown and described what are at present considered the preferred embodiments of the invention, it will be obvious to those skilled in the art that various changes and modifications may be made therein without departing from the scope of the invention as defined by the appended claims.

We claim:

1. In a method of fabricating a numeric readout tube mount structure having a plurality of illuminable anode segments the steps comprising: first forming said anodes as a single integral unit having substantially the configuration of a figure eight with opposed, spaced apart side sections; opposed spaced apart top and bottom sections connected to said side sections; and a middle section parallel to said top and bottom sections also connected to said side sections, each of said sections being provided with an inwardly projecting tab; bending said tabs to extend away from the plane of said sections at an angle of substantially 90°; forming an intermediate mounting member comprising a plurality of leads having first and second ends projecting from a glass spacer positioned intermediate said ends; forming at least some of the first ends of said leads to positions accommodating said tabs; attaching said formed first ends of said leads to said tabs; forming said integral unit into a plurality of electrically isolated segments by cutting out portions thereof where said top, bottom, and middle sections join said side sections; and coating the surface of said formed segments with phosphor.
2. The invention of claim 1 wherein said number of electrically isolated segments is seven.
3. The invention of claim 1 wherein said glass spacer is parallelepipedonal.
